UNITED STATES PATENT OFFICE

2,618,933

HYDRAULIC APPARATUS

Cecil E. Adams, Columbus, Ohio, assignor to The Denison Engineering Company, Columbus, Ohio, a corporation of Ohio

Original application February 24, 1947, Serial No. 730,504. Divided and this application December 15, 1948, Serial No. 65,461

9 Claims. (Cl. 60—97)

1

This invention relates generally to hydraulic apparatus and is more specifically directed to a hydraulically actuated, stock-feeding attachment for hydraulic presses.

This application is a true division of my co-pending application, Serial No. 730,504 for Hydraulic Apparatus filed February 24, 1947.

One of the objects of this invention is to provide a feeding mechanism which will feed stock to a press or other device for performing an operation on the stock, which feeding mechanism will operate in timed sequence with the press and will uniformly accelerate and decelerate the stock in its movement thereby avoiding slippage between the feeding means and the stock with consequent greater accuracy in the feeding operation.

Another object of the invention is to provide a feeding mechanism having a fluid motor and control valve mechanism therefor which will be operative to cause the fluid motor to perform separate feeding cycles of not more than one revolution in duration spaced by inactive or rest periods in which the device served by the feeding mechanism performs an operation on the stock fed thereto.

A further object of the invention is to provide a feeding mechanism having a feed roll, a fluid motor and motion transmitting means therebetween which will provide for equal successive increments of rotation of the feed roll, the motion-transmitting means being adjustable to permit variation in the length of the increments of rotation whereby more or less stock will be fed depending upon the operations being performed.

A still further object of the invention is to provide a feeding mechanism having a feed roll, a fluid motor and motion-transmitting means therebetween, the latter means including a one-way clutch between the feed roll and driver therefor, a crank on the driver, an eccentric operated by the fluid motor, and a connecting rod between the eccentric and the crank, the elements being so arranged that rotation of the eccentric causes a back and forth rocking movement of the crank, the one-way clutch serving to transmit motion from the driver to the feed roll when the crank moves in one direction and to avoid the transmission of motion to the feed roll when the crank moves in the opposite direction.

Another object is to provide a combined hydraulic press and feeding mechanism having control mechanism which causes the automatic reciprocation of the ram of the press and the automatic intermittent operation of the feeding

2

mechanism, the operations of the devices being alternately performed to avoid interference.

An object also is to provide a hydraulic system for the combined press and feeding mechanism mentioned in the preceding paragraph, the system having a source of fluid pressure, a reversing valve responsive to fluid pressure for initiating the operation of the press, another valve device actuated by the press to direct fluid from the pressure source to the feeding mechanism and a third valve device operated by the driving motor of the feeding mechanism for applying fluid pressure to said reversing valve to start the operation of the press when a feeding operation has been concluded.

Further objects and advantages of the present invention will be apparent from the following description, reference being had to the accompanying drawings wherein a preferred form of embodiment of the invention is clearly shown.

In the drawings:

Fig. 1 is a perspective view of a feeding mechanism formed in accordance with the present invention showing the same attached to a press.

Fig. 2 is an end elevational view of the feeding mechanism shown in Fig. 1.

Figs. 3 and 4 are vertical sectional views taken through the feeding apparatus showing different features of construction.

Fig. 5 is a horizontal longitudinal sectional view taken through the feeding mechanism on the plane indicated by the line V—V of Fig. 4.

Fig. 6 is a diagrammatic view of the hydraulic system employed in the press and the feeding mechanism therefor.

Referring more particularly to the drawings numeral 20 designates generally the feeding mechanism forming the subject matter of the present invention. This feeding mechanism may be used as an accessory on presses of various types, but for purposes of illustration, it is shown in the drawings as an accessory for a hydraulic press, this device being indicated generally by the numeral 21. The press 21 includes a frame 22 having a bolster section 23, an upright column 24, and a head section 25, the head and bolster sections projecting forwardly from the column 24. The head section has a power cylinder 26 supported therein, this cylinder receiving a piston 27 from which a ram 28 projects toward the bolster section 23. When movement is transmitted to the piston 27 to cause reciprocation thereof in the cylinder 26, the ram 28 will be moved toward and away from the bolster section.

The head section also receives a control valve 30 which may be of any suitable type, the one illustrated being of the type shown in co-pending application, Serial No. 600,736, filed June 21, 1945, now Patent No. 2,561,766, issued July 24, 1951. This valve, shown diagrammatically in Fig. 6, operates to control the flow of fluid from a pressure source 31 to the power cylinder 26 to secure the automatic operation of the piston and ram. The pressure source 31 includes a reservoir 32, a motor driven pump 33 and a relief valve 34, the latter being adjustable to vary the pressure in the hydraulic system at which the discharge from the pump 33 will be bypassed back to the reservoir 32. A fluid line 35 extends from the pressure source to the control valve 30, this fluid line being in open communication with the inlet port 36 of the valve 30. While this valve has been described in detail in the patent above referred to, it will also be described herein sufficiently to facilitate the understanding of the present invention.

Valve 30 includes a body casing 37, which is formed with a pair of vertically extending bores 38 and 40. Body 37 is also formed with a plurality of annular grooves 41 to 47, which are spaced longitudinally of, and open into, the bore 38. The body is further formed with annular grooves 48, 49, and 50, which are spaced longitudinally of, and open into, the bore 40. Bore 38 receives for sliding movement a spool 52 having an internal chamber 53 and a plurality of longitudinally spaced sets of ports 54 to 60, inclusive, formed in the side wall thereof. Certain of these ports register with certain of the grooves 41 to 47 in various positions of movement of the spool 52 in the bore 38. The upper end of the chamber 53 is closed by a cap 62 in which a recess 63 is formed, this recess opening to the underside of the cap. The upper end of the coil spring 64 is received in the recess 63, the lower end of this spring being disposed in a socket 65 formed in a shuttle valve 66 disposed for sliding movement in the chamber 53 of spool 52. The shuttle valve 66 comprises a cylindrical member having an external groove 67 formed in the wall thereof, intermediate the ends of the cylinder, this groove providing spaced heads 68 and 70 on the spool. The shuttle valve is also provided at the head portion 68 with transversely extending ports 71 which communicate at their inner ends with a chamber 72. Axial ports 73 and 74 are formed in the shuttle valve, the former extending from the chamber 72 to the socket 65 and the latter extending from the chamber 72 to the lower end of the shuttle valve. The coil spring 64 normally retains the shuttle valve in its lowered position with the lower end thereof in engagement with the bottom wall of the chamber 53 in spool 52.

The spool 52 has a rod 75 projecting from its lower end through a cap 76 secured to the bottom of the body 37. This rod is connected at its lower end to another rod 77 commonly termed the shipper rod, this rod receiving a collar 78 which is adjustably secured to the rod and is engaged at certain stages of operation of the ram 28 by the end of an arm 80 secured for movement with the ram. When the ram moves in an upward direction and approaches the upper limit of its travel, the arm 80 will engage the collar 78 and move the rod 77 in an upward direction. This movement is transmitted by rod 75 to the valve 52 causing the latter to move to a position where fluid flow to the lower end of the power cylinder to effect upward movement of the ram will

be interrupted. When this event occurs, the ram will come to rest in a raised, inoperative position ready for another cycle of operation. Ports 58 in spool 52 communicate at all times with groove 45, which is in open communication with the inlet port 36, thus fluid from the pressure source may flow through the ports 58 into the chamber 53 at the groove 67 formed in the shuttle valve. When the parts of the valve are in the position shown in Fig. 6, which position will be assumed when the ram 28 is at rest, fluid admitted to groove 67 may flow outwardly from the chamber 53 through ports 57 into groove 44.

Body 37 has a drilled opening 81 formed in one side thereof, which opening communicates at its inner end with the groove 44 so that fluid admitted thereto may flow from the groove to bore 40 and from the latter through the outer portion of opening 81 to a line 82. The fluid admitted to the bore 40 when the parts are in the positions shown in Fig. 6 is prevented from flowing longitudinally thereof by a spool 83 disposed for movement in the bore 40. This spool has longitudinally spaced heads 84 and 85 which engage the side walls of the bore 40 and control communication between the portion of the bore 40 between heads 84 and 85 and the groove 49, head 84 serving at all times to prevent communication between that portion of the bore and the groove 48.

Normally, the spool 83 is yieldably retained in a centered position by coil springs 86 and 87 disposed at the ends of the spool between the end caps for the body 37 and shoulders formed on the spool and a spring abutment 88. When in the centered position, under the influence of the springs, the space around the spool 83 between the heads 84 and 85 will be in communication with groove 46 surrounding bore 38. Groove 46 is connected, when the parts of the valve mechanism are in position to maintain the mechanism inoperative, with the reservoir 32 through ports 59 in spool 52, chamber 53, ports 60, grooves 47 and 50 and exhaust line 90, thus fluid under pump pressure will be bypassed directly to the reservoir 32 when the mechanism is idle, without imposing a burden on the pump-operating motor. Spool 83 is adjusted in bore 40 by an eccentric pin 91 supported for oscillation in the lower portion of the body 37, a shaft 92 projecting from the support for the eccentric pin to the exterior of the mechanism to effect the manipulation of the pin. By such rotation of the support, the spool 83 may be lowered from its centered position, wherein pump flow is discharged to reservoir 32 to the position shown in Fig. 6 which provides for automatic operation of the press and the feeding mechanism 20.

When the spool 83 is in the latter position and spool 52 also is in the position shown, pump fluid 60 will be directed through the line 82 to a second control valve mechanism 93 which is attached to the rear end of a fluid motor 94 employed to drive the feeding mechanism. Fluid motor 94 may be of any suitable type, the one illustrated having an inlet port 95 and an outlet port 96. Valve 93 has a passage 97 which establishes direct communication between the line 82 and the motor inlet 95, thus, fluid supplied to line 82 will flow directly into the fluid motor to effect the operation thereof. This fluid will be exhausted through the outlet port 96 into a passage 98 formed in valve 93. Passage 98 leads to the outlet port 100 of the valve mechanism, 93, which outlet port is connected by a line 101 with reservoir 32. As long as fluid is permitted to flow to

the fluid motor 94 and outwardly through the outlet passage 98, port 100 and line 101 to the reservoir, the fluid motor will operate. The rate of operation may be controlled through the adjustment of a bypass valve 102 which is disposed in a passage 103 extending between the passages 97 and 98 in the valve 93. When the fluid motor 94 operates, due to the flow of fluid therethrough, the operating shaft 104 thereof will be rotated. This shaft projects from the fluid motor 94 and is keyed at its outer end to a hub 105 journaled in bearings 106. The hub has an eccentric portion 107 the purposes of which will appear as the description proceeds.

The outer portion of the hub 105 is provided with an enlargement 108 in which a dove-tail groove 109 is formed. This groove slidably receives a member 110 from which a crank pin 111 projects. The ends of the groove 109 are closed by plates 112 which support for rotation an adjusting screw 112-A, this screw being threaded through the member 110 and serving, when rotated, to vary the longitudinal position of the member 110 in the slot. In this manner, the distance between the axis of rotation of the hub 105 and the crank pin may be varied. Crank pin 111 pivotally receives one end of a connecting rod 113, the opposite end of which is similarly connected to a pin 114 on a crank arm 115; this crank arm is secured to a shaft 116 which is in turn keyed to the driver section 117 of a one-way clutch.

This clutch includes a driven section 118 which is formed with or suitably secured to a feed roll 120, the latter being journaled for rotation in a frame 121. Motion is transmitted from the driver section 117 to the driven section 118 through the provision of spring-pressed balls 122 disposed between angular surfaces 123, formed on the driver, and the inner surface of the driven section 118. When the driver section is revolved in the direction of the arrow in Fig. 3 the balls 122 will be wedged between the inclined surfaces 123 and the driven section locking the sections together for rotation in unison. Movement of the crank arm 115 to cause rotation of the section 117 in this direction is caused by rotation of the driving motor and the motion of the crank end 109 operated thereby. This movement takes place during one-half a revolution of the motor shaft. During the other half of such a revolution, the driver section 117 is revolved in the opposite direction. Such movement will not be transmitted to the driven section and feed roll since the one-way clutch permits relative movement between these elements when the motion of the driving section is reversed.

The feed roll is positively prevented from backing up or overrunning by a brake 124 comprising a lined band 125 which is connected at one end to the frame as at 126 and at the opposite end to a spring-pressed block 127, this block being engaged by a rod 128 which is secured to a split collar 129 surrounding the eccentric portion 107 of the hub 105. The eccentric 107 is so related to the crank pin 111 that the brake will be applied at the proper time to prevent overrun or reverse movement of the feed roll. The degree of rotation of the feed roll during each forward movement of the driver member is regulated by the adjustment of the member 110 relative to the axis of rotation of the hub 105.

In order that the stock being fed by the feeding mechanism will be frictionally held in contact with the feed roll, there is provided a pressing roll 131 which is journaled in suitable bearings

132 carried by the frame 121. The presser roll 131 is resiliently urged toward the feed roll by coil springs 133 disposed between the upper sections of the bearings 132 and adjusting screws 134. 5 Through the adjustment of the screws 134, the force of the springs 133 may be varied to cause more or less friction between the stock and the feed roll. A pair of guide rollers 135 are mounted for rotation about vertical axes on a transversely extending web of the frame at the inlet side of the feed roll, to center the stock between the feed rolls, these guide rollers also tending to eliminate friction which might affect the feeding operation.

In the operation of the press and feeding mechanism, the press ram and feeding rolls are alternately operated, the latter performing a feeding operation for each revolution of the driving motor 94. To effect the alternate operation of the ram and feed roll, the valve 93 is provided with a 15 poppet 137 disposed in the passage 98. This poppet is normally maintained in an open position by a spring 138 in order that the fluid discharged from the fluid motor may flow to exhaust without appreciable obstruction. After the feed roll has 20 advanced the stock toward the ram and the driving motor 94 executes a portion of the second half of the revolution, the poppet 137 is actuated to interrupt the flow of fluid to exhaust and direct the same through a second outlet or control port 25 140. To close poppet 137, the motor shaft 104 is provided with a cam 141 which engages a roller 142 provided on the end of a plunger 143, this member being disposed for sliding movement in the frame work of the feeding mechanism. The 30 outer end of the plunger 143 engages one arm 144 of a bell crank 145 the second arm 146 of which engages one end of a push rod 147; this push rod in turn, engages the outer end of a stem formed with poppet 137 and projecting from the casing 35 of the valve 93. A suitable compensating connection 148 forms a part of the push rod 147 to absorb additional movement, after the poppet is closed, and prevent injury to the mechanism. After the 40 poppet valve has been closed, fluid discharged from the fluid motor 94 will flow through line 150 to groove 42 in valve body 37. This groove communicates with groove 42 which in turn communicates through ports 54, with chamber 53 at the lower end of the shuttle valve 66. Fluid thus 45 introduced into the lower end of the chamber 53 will move the shuttle valve upwardly in opposition to the force of the spring 64 until groove 67 in the shuttle valve establishes communication 50 between the inlet line 35 and the groove 46 through groove 45 and ports 58 and 59. 55

After shuttle valve 66 has been elevated the flow of exhaust fluid from motor 94 will be obstructed with the effect of stalling the motor. Before this motor stalls, however, the volume of 60 fluid necessary to elevate the shuttle valve exhausted by the motor is sufficient to permit motor 54 to advance far enough to cause the high point on cam 141 to pass follower 142. This action would normally permit poppet 137 to return to an open position but due to the pressure existing beneath the shuttle valve, in line 150 and passage 65 98 the poppet is retained in closed position.

Since groove 46 is connected by line 151 with the upper end of power cylinder 26, the placing 70 of the shuttle valve in an elevated position will connect the source of fluid pressure with the upper end of the power cylinder. At this time also, the lower end of the power cylinder will be in communication with the reservoir 32. This communication takes place through line 152,

groove 43, ports 55, or 56 in the spool 52, ports 71 in the shuttle valve, chamber 72, passage 73, socket 65, ports 60, grooves 47 and 50, and line 90. Flow of fluid along this path will be restricted due to the reduced size of the passage 73 causing a back pressure to build up in the chamber 72, the lower end of the power cylinder and the passages connecting these members. This back pressure is transmitted to the lower end of the chamber 53 through passage 74 and serves to maintain the pressure previously introduced through line 150. The shuttle valve 66 will thus be retained in an elevated position and poppet 137 will be held closed during the downward movement of the ram. When movement in this direction is initiated, the arm 80 will move away from the collar 78 permitting the shipper rod and valve spool 52 to move downwardly in response to the force of a spring 153 disposed in the valve casing 37 between a washer 154 and a collar 155 surrounding rod 75, until ports 57 move out of registration with groove 44, at this time the path of fluid flow to the fluid motor 94 will be obstructed. Full pump volume will then be available for the operation of the ram and fluid motor 94 will remain idle until arm 80 again engages collar 78 during the return movement of the ram, and moves valve spool 52 to reestablish communication between ports 57 and groove 44. When this communication is reestablished, the feeding mechanism will again be operated and the ram will remain stationary until another charge of fluid under pressure is supplied to the underside of the shuttle valve to initiate another operation of the ram.

Return or upward movement of the ram occurs after the ram has exerted the force determined by the setting of relief valve 34. When this valve operates to spill fluid directly from the pump 33 to reservoir 32 the ram ceases to move in a downward direction and the exhaust flow from the lower end of the power cylinder ceases. The back pressure is then dissipated through passages 73 and 74 and shuttle valve 66 is moved to its lowermost position by the force of spring 64. When the back pressure is dissipated, spring 138 moves valve 137 to an open position also and the mechanism is in condition for another cycle of operation which will occur as soon as the ram reaches a fully retracted position if the spool 83 is properly positioned as previously mentioned.

From Fig. 6 it will be noted that line 150 contains a restriction 156. This restriction serves to insure the retention of poppet 137 in closed position immediately after it has been closed by the push rod 147 even though the push rod is retracted due to the high point on cam 141 passing follower 142. Inasmuch as a poppet valve is used which poppet will readily open because of the relatively slight displacement of fluid, the use of the restriction in line 150 is desirable. This restriction is located in close relationship to port 140 and although it serves to obstruct fluid flow to retain poppet valve closed, such obstruction is insufficient to deleteriously affect the opening of the poppet valve when the ram stops moving downwardly and the shuttle valve drops.

The cam 141 is provided with a relatively sharp projection to reduce the tendency of the device to stop with the poppet valve closed.

From the foregoing it will be apparent that a feeding mechanism has been provided which will operate to successively feed stock to a ram or other device for performing operations thereon.

It will also be apparent that a hydraulic system has been provided for both the press and the feeding mechanism, which system provides for the alternate operation of the press ram and the feeding mechanism, each of these elements being retained in inactive condition during the active condition of the other. Due to this alternate operating arrangement no interference of one mechanism with the other can result.

10 I claim:

1. A hydraulic system comprising a source of fluid pressure; a power cylinder having a ram; a fluid motor; valve means between said fluid pressure source and said power cylinder, said valve means being operative to direct fluid to said power cylinder to cause a single cycle of operation thereof and to then direct fluid to said fluid motor; and a second valve means operative to direct fluid discharged from said fluid motor to exhaust during a portion of a cycle of operation thereof and to thereafter direct such exhaust to said first valve means during another portion of the cycle of operation of said motor to initiate the operation of said power cylinder.

25 2. A hydraulic system comprising a source of fluid pressure; a power cylinder having a ram; a fluid motor; valve means between said fluid pressure source and said power cylinder, said valve means being operative to direct fluid to said power cylinder to cause the advance and retraction of the ram thereof and to then direct fluid to said fluid motor; a second valve means operative to direct fluid discharged from said fluid motor to exhaust during a portion of a cycle of operation thereof; and means operated by said fluid motor during another portion of the cycle of operation thereof to actuate said second valve means to thereafter direct fluid discharged from said fluid motor to said first valve means to dispose the same in position to interrupt the flow of fluid to said motor and initiate the operation of said power cylinder.

30 3. A hydraulic system comprising a source of fluid pressure; a power cylinder having a ram; a fluid motor; valve means between said fluid pressure source and said power cylinder, said valve means being operative to direct fluid from said source to said power cylinder to cause a cycle of operation thereof and having an element operated by said ram adjacent the termination of said cycle of operation to direct fluid from said pressure source to said fluid motor; and a second valve means operative to direct fluid discharged from said fluid motor to exhaust during a portion of a cycle of operation thereof, said second valve being actuated by said fluid motor adjacent the termination of a cycle of operation thereof to direct fluid discharged from said motor to said first-mentioned valve means to interrupt fluid flow to said fluid motor and initiate a cycle of operation of said power cylinder.

35 4. A hydraulic system comprising a source of fluid pressure; a power cylinder having a ram; a fluid motor; valve means between said fluid pressure source and said power cylinder, said valve means being operative to direct fluid from said source to said power cylinder to cause a cycle of operation thereof consisting of the advance and retraction of said ram and then direct fluid from said pressure source to said fluid motor; a second valve means normally operative to direct the discharge from said fluid motor to exhaust; means actuated by said fluid motor at one stage in each revolution thereof to

shift said second valve means to momentarily direct fluid discharged from said fluid motor to the first-mentioned valve means to terminate fluid flow to said fluid motor and initiate an operation of said power cylinder; and means operated by said ram adjacent the termination of each cycle of operation of said power cylinder to interrupt the flow of fluid to said power cylinder and resume the flow to said fluid motor.

5. A hydraulic system comprising a source of fluid pressure; a power unit having a ram; a fluid motor; valve means between said fluid pressure source and said power cylinder, said valve means having an element responsive to fluid pressure to initiate the operation of said power unit; flow directing means in said valve means actuated by said ram adjacent the termination of a cycle of operation to connect said fluid motor with said fluid pressure source; a second valve means normally operative to direct the discharge from said fluid motor to exhaust; and means for transmitting movement from said fluid motor adjacent the end of a cycle of operation thereof to said second valve means to interrupt the flow of discharge fluid to exhaust and apply the same to the fluid pressure responsive element of the first-mentioned valve means to initiate a cycle of operation of said power unit.

6. A hydraulic system comprising a source of fluid pressure; a power unit having a ram; a fluid motor; valve means between said fluid pressure source and said power cylinder, said valve means having an element responsive to fluid pressure to initiate the operation of said power unit; flow directing means in said valve means actuated by said ram adjacent the termination of a cycle of operation to connect said fluid motor with said fluid pressure source; a second valve means normally operative to direct the discharge from said fluid motor to exhaust; and cam means actuated once during each revolution of said fluid motor to close said second valve means and interrupt the flow of discharge fluid to exhaust and apply the same to the fluid pressure responsive element of the first-mentioned valve means to initiate a cycle of operation of said power unit.

7. A hydraulic system comprising a source of fluid pressure; a power unit having a ram; a fluid motor; valve means between said fluid pressure source and said power cylinder, said valve means having an element responsive to fluid pressure to initiate the operation of said power unit; flow directing means in said valve means actuated by said ram adjacent the termination of a cycle of operation to connect said fluid motor with said fluid pressure source; a second normally open valve means in the outlet of said fluid motor; a branch line extending from said fluid motor outlet in advance of said second valve means to the pressure responsive element of said first-mentioned valve; and means operated once during each revolution of said fluid motor to close said second valve means to interrupt the discharge of fluid from said fluid motor to exhaust

and direct the same through the branch line to said fluid pressure responsive element of the first-mentioned valve means to initiate a cycle of operation of said power unit.

5. 8. A hydraulic system comprising a source of fluid pressure; a power unit having a ram; a fluid motor; valve means between said fluid pressure source and said power cylinder, said valve means having an element responsive to fluid pressure to initiate the operation of said power unit; flow directing means in said valve means actuated by said ram adjacent the termination of a cycle of operation to connect said fluid motor with said fluid pressure source; a second normally open valve means in the outlet of said fluid motor; a branch line extending from said fluid motor outlet in advance of said second valve means to the pressure responsive element of said first-mentioned valve; a flow resisting element 10 in said branch line and means operated once during each cycle of operation of said fluid motor to close said second valve means to interrupt the discharge of fluid from said fluid motor to exhaust and direct the same through the branch 15 line to said fluid pressure-responsive element of the first-mentioned valve means to initiate a cycle of operation of said power unit.

9. A hydraulic system comprising a source of fluid pressure; a power unit having a ram; a fluid motor; valve means between said fluid pressure source and said power cylinder, said valve means having an element responsive to fluid pressure to initiate the operation of said power unit; flow directing means in said valve means actuated by said ram adjacent the termination of a cycle of operation to connect said fluid motor with said fluid pressure source; a second valve means normally operative to direct the discharge from said fluid motor to exhaust; a by-pass valve in said second valve means, said by-pass valve being adjustable to vary the quantity of fluid admitted to said fluid motor to control the rate of operation thereof; and means for transmitting movement from said fluid motor adjacent the end of a cycle of operation thereof to said second valve means to interrupt the flow of discharge fluid to exhaust and apply the same to the fluid pressure responsive element of the first-mentioned valve means to initiate a cycle of operation of said power unit.
